UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

TRIMMING MECHANISM FOR SEWING MACHINES.

Application filed October 8, 1918. Serial No. 257,369.

To all whom it may concern:

Be it known that I, SAMUEL GEORGE TATE, a citizen of the United States, residing at Chicago, in the county of Cook, State of Illinois, have invented certain new and useful Improvements in Trimming Mechanism for Sewing Machines, of which the following is a description, reference being had to the accompanying drawing and to the figures of reference marked thereon.

The invention relates to new and useful improvements in trimming mechanisms for sewing machines, and more particularly to a trimming mechanism having horizontally disposed trimming blades for trimming upturned edges of fabric sections which are to be subsequently abutted or slightly overlapped and then united to form a "flat seam."

In certain classes of garment making, it is very desirable to stitch some of the seams on machines having a suspended work-supporting arm, off from the end of which the stitched garment section passes. This enables tubular sections to be formed.

An object of the present invention is to provide a sewing machine having a standard, a forwardly projecting arm carried thereby, a depending support at the outer end of the arm, and a work support suspended by said depending support and terminating adjacent the standard with a trimming mechanism having horizontally disposed trimming blades operated by a main shaft extending through the standard.

In the drawings, which show by way of illustration one embodiment of the invention,

Figure 1 is a vertical sectional view, substantially on the line of feed and showing a sewing machine having my improvement embodied therein;

Figure 2 is a view partly in horizontal section and partly in top plan, showing the machine;

Figure 3 is a detail, partly in section, through the work supporting arm and partly in front elevation—showing the parts of the trimming mechanism adjacent the presser foot;

Figure 4 is a view partly in section and partly in top plan—showing the presser foot and a portion of the trimming mechanism adjacent thereto.

The machine in which my invention is em-

bodied consists broadly of a main standard, which carries a suspended work supporting arm. The material to be stitched is fed off from the end of this work supporting arm. The work supporting arm is carried by a section of the frame, which, as shown in the drawings, also supports the needle bar carrying the needles for stitching the fabric sections. The needle bar is operated by a cross-shaft which in the present embodiment of the invention is the main shaft of the machine. The material is held on the work support by a presser foot. The trimming members operate upon the upturned fabric edges of the material, which subsequently passes underneath the presser foot and are stitched together to form a flat seam. One of these trimming members is stationary and the other is movable and the movable trimming member is carried by a yoke journaled to swing on the auxiliary bar which guides the presser foot, and this yoke is in turn operated by a direct connection with the main shaft which operates the needles.

Referring more in detail to the drawings, I have shown my improved trimming mechanism as applied to a sewing machine having a supporting standard 1, from which a laterally projecting arm 2 projects, and this arm 2 carries a forwardly projecting arm 3, having a depending support 4, which in turn carries the work-supporting arm 5 of the machine.

Mounted in the standard and extending through the projecting arm 2 is a main shaft 6. This main shaft 6 operates a cross-shaft 7 in the arm 3, and, this in turn through suitable connections, operates the feeding mechanism, which is located in the arm 5, and also the looper mechanism carrying the looper co-operating with the needles. The arm 5 is suspended so that the material to be stitched may be placed underneath the same and the edges to be joined are brought over the top of the arm and led underneath the presser foot, which is indicated at 8 in the drawings. This presser foot is carried by a presser bar 9, which is mounted in suitable bearings in the arm 2 of the frame. Adjacent the presser bar 9 is a guide bar 10, which is connected at 11 to the presser foot and which may also be suitably connected to the presser bar 9. This guide bar is of the usual construction and serves not only

to guide the presser bar in its up and down movements, but also to prevent the presser foot from swinging laterally on its support bar 9 owing to the strain thereon of the 5 trimming mechanism.

The stationary trimming blade is indicated at 12 in the drawings. This blade is clamped by a screw 13 and a cooperating clamping plate to the presser foot. The 10 presser foot is formed with a dove-tailed recess to receive the stationary blade, which is similar in shape, as clearly shown in Figure 1 of the drawings. This is the usual manner of securing a stationary blade to the 15 presser foot. The presser foot is formed with a guiding slot 14, through which the upturned edges of the fabric sections which are to be joined pass. The stationary trimming blade 12 has its cutting edge terminating substantially at the guiding slot 14, so that the upturned edges will pass along the cutting edge of this stationary blade. Co-operating with the stationary blade is a 20 movable trimming blade 15. These blades are horizontal and the movable trimming blade crosses the guiding slot 14 and co-operating with the stationary blade trims the upturned edges of the fabric sections. After the edges of the fabric sections have 25 been trimmed, they are brought either to abutted or overlapped relation and then are stitched by a stitching mechanism, as herein shown, consisting of three needles 16, which pass through a suitable opening in the presser foot and the looper mechanism, referred to above, cooperates with these needles. As herein shown, the looper mechanism includes a single looper 17, carried by a shaft 18, which is operated by suitable 30 connections from the shaft 7, above described. The needles 16 are carried by a needle bar 19 which reciprocates in suitable bearings 20-20 in the arm 2 of the frame. The main shaft 6 is provided with a crank 21. A link 45 22 cooperates with this crank and is connected with a lever 23, which in turn is connected by a link 24, with a needle bar 20.

The movable blade 15 of the trimming mechanism is carried by an arm 25. This 50 arm is formed integral with a collar 26. This collar 26 is a part of a yoke 27. The yoke 27 has an upper collar 28 and the collars 26 and 28 are freely journaled on the guide bar 10. The guide bar 10 has two 55 fixed collars 29 and 30, between which the yoke collars are placed. The yoke 10 has an upwardly extending arm 31, carrying a ball stud 32. Cooperating with the ball stud 32 is an eccentric strap 33, see Figure 2, which 60 in turn engages an eccentric 34 on the shaft 6. As this shaft 6 rotates, the eccentric will through the eccentric strap 33, vibrate the yoke 27, and this in turn will vibrate the arm 25 and the trimming blade 15 carried there- 65 by. The trimming blade 15 is held in a

supporting head 35, carried by the arm 25 by means of a set screw 36.

From the above, it will be apparent that I have provided a very short and direct train of mechanism for operating the movable trimming blade. There is only one movable connecting element between the eccentric and the trimming blade and this is the ball stud connection between the yoke and the eccentric strap. This enables a very 70 direct and positive thrust to be imparted to the trimming blade resulting in a very efficient trimming of the fabric sections, also, resulting in little wear or vibration of the parts. 80

It will be obvious that minor changes in the details of construction may be made without departing from the spirit of the invention, as set forth in the appended 85 claims.

Having thus described my invention, what I claim as new and desire to secure by Letters Patent, is:—

1. The combination of a standard, a forwardly projecting arm carried thereby, a 90 depending support at the outer end of said arm, a work-supporting arm suspended by said support and extending toward and terminating adjacent said standard, a presser foot, a presser bar supporting said foot, a 95 guide bar connected to the presser foot, a stationary trimming member carried by said presser foot, a horizontally disposed movable trimming member co-operating therewith, a yoke mounted to swing on said guide 100 bar and having an arm carrying said movable trimming member, an arm projecting from the upper end of said yoke, a cross shaft extending through said standard, and means operated by said shaft and connected 105 with the arm at the upper end of the yoke for oscillating the trimming member.

2. The combination of a standard, a forwardly projecting arm carried thereby, a 110 depending support at the outer end of said arm, a work-supporting arm suspended by said support and extending toward and terminating adjacent said standard, a movable trimming member, a vertical support, a yoke having spaced collars mounted to oscillate 115 on said vertical support, fixed collars on said support for retaining the yoke in vertical position, an arm integral with one of said collars and carrying said movable trimming member, an arm projecting from the 120 upper end of said yoke, a cross shaft extending through said standard; and devices operated by said shaft and connected to said arm for vibrating the yoke.

3. The combination of a standard, a forwardly projecting arm carried thereby, a 125 depending support at the outer end of said arm, a work-supporting arm suspended by said support and extending toward and terminating adjacent said standard, a movable 130

trimming member, a vertical support, a yoke having spaced collars mounted to oscillate on said vertical support, fixed collars on said support for retaining the yoke in vertical position, an arm integral with one of said collars and carrying said movable trimming member, an arm projecting vertically from said yoke, a cross shaft extending through said standard, an eccentric on said shaft, and an eccentric strap co-operating with said eccentric and connected with said arm for vibrating said yoke.

4. The combination of a standard, an arm projecting laterally therefrom, a forwardly projecting arm carried by the laterally extending arm, a depending support at the outer end of said forwardly projecting arm, a work support carried at the lower end of said depending support and sustained thereby and extending toward and terminating underneath the laterally ex-

tending arm, a movable trimming member, a vertical support, a yoke having spaced collars mounted to oscillate on said vertical support, fixed collars on said support for retaining the yoke in a predetermined vertical position, an arm integral with one of said collars and carrying the movable trimming member, an arm projecting vertically from said yoke, a cross shaft extending through the standard, and the laterally projecting arm, an eccentric on said cross shaft, an eccentric strap cooperating with said eccentric and connected directly with the arm for vibrating the yoke.

In testimony whereof, I affix my signature, in the presence of two witnesses.

SAMUEL GEORGE TATE.
